UNITED STATES PATENT OFFICE.

DAVY VANCE SICKMAN, OF DENVER, COLORADO.

HYDRAULIC CARTRIDGE.

1,144,005.

Specification of Letters Patent. Patented June 22, 1915.

Application filed April 13, 1914, Serial No. 831,410. Renewed November 16, 1914. Serial No. 872,496.

To all whom it may concern:

Be it known that I, DAVY VANCE SICKMAN, citizen of the United States, residing in the city and county of Denver and State of Colorado, have invented certain new and useful Improvements in Hydraulic Cartridges, (Case B;) and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to improvements in hydraulic cartridges, of the class employed for breaking down coal and other material in mines. This method is particularly advantageous for breaking down coal for the reason that it avoids as far as is possible, the formation of slack or dust. In coal mines, it is exceedingly desirable that as little dust as possible be formed in the mine, owing to the fact that coal dust is an explosive. These cartridges make it practicable to break down coal in large bodies and by reason of the fact that water is employed as the force which actuates the movable elements of the cartridge, the formation of dust is to a great degree prevented.

In my present invention, I employ elongated pistons, preferably ellipsoidal in shape, which are located in chambers of corresponding shape which are formed in the bars or cylindrical casings employed in devices of this character. In my present improvement, I have shown a cartridge in which the pistons and their corresponding chambers vary in size, the size progressively increasing from front to rear, these terms being employed in relation to the position of the piston when inserted in the hole formed in the coal. The pistons may also be unequally spaced.

This invention also contemplates the forming of the pistons of equal size where they are unequally spaced.

Having briefly outlined my present invention, I will proceed to describe the same in detail, reference being made to the accompanying drawing, in which is illustrated an embodiment thereof.

In this drawing, Figure 1 is a vertical longitudinal section taken through a cartridge of my improved construction. Fig. 2

is an underneath view of the same. Fig. 3 is a view similar to Fig. 2, but showing a slightly modified form of construction. Fig. 4 is a view similar to Figs. 2 and 3, but showing still another modification. Fig. 5 is a view illustrating the manner of preparing the coal, for instance, within a mine, preparatory to the use of my improved cartridges for breaking down the same.

The same reference characters indicate the same parts in all the views.

Let the numeral 5 designate the body or bar of the cartridge which is preferably cylindrical in shape. Referring first more particularly to Figs. 1 and 2, the bar 5 is provided with a number of chambers 6, 7 and 8, the said chambers increasing progressively in volume from front to rear, the rearmost being the largest, the next in advance somewhat smaller and the foremost smallest. This construction and arrangement of cartridges is based on the proposition that the greatest force exerted for breaking down the coal should be at the extreme rear of the opening in which the cartridge is located. The logic of this proposition will be readily understood by an examination of Fig. 5 of the drawing. These piston chambers as heretofore stated, are elongated in shape and the pistons 9, 10 and 11 located therein are of counterpart shape. Each piston is provided with a gasket or cup leather 12, which is somewhat larger than the area of the chamber, its edge being turned upwardly, as is common in devices of this class, in order to form a fluid tight joint between the piston and the walls of its chamber. These gaskets are held in place by plates 13 which are secured by screws 14. Each piston is provided at its opposite extremities with grooves 15, adapted to receive short tongues 16 formed on stop plates 17 which are secured to the opposite extremities of the bar 5 and to the partitions separating the piston chambers by means of securing screws 18, or other suitable fastening devices. At the bottoms of the grooves 15, offsets 19 are formed which are adapted to engage the tongues 16, to prevent the pistons from entirely escaping from their chambers except when necessary. The stop plates 17 are readily removable when it becomes necessary or desirable to detach the pistons from the bar in which they are located.

The water which constitutes the force for actuating the pistons to perform the coal

2
breaking function, is introduced through a nozzle or conduit 20, provided with an orifice 21, which registers with an orifice 22 formed in the bar and leading forwardly 5 through the top of the cartridge longitudinally toward the rear. Communicating with this orifice 22 are ports 23, 24 and 25, which lead from the orifice 22 to the respective piston chambers. By virtue of this 10 construction, the water will be simultaneously or approximately so, introduced into all the chambers of the cartridge, whereby the pistons are simultaneously ejected for breaking down coal. In Figs. 1 and 2, the 15 piston chambers are equally spaced by partitions 26. In Fig. 3, the pistons are of the same construction as disclosed in Figs. 1 and 2, that is to say, they progressively diminish in size from the rear toward the 20 front, but they are unequally spaced. For instance, the partition separating the rearmost piston chamber from that next in advance, is shorter than that which separates the foremost piston from the one next in 25 the rear. Attention is called to the fact that in the cartridges illustrated in the drawing, three pistons are shown for each cartridge. It is evident that the number of pistons may be increased or diminished as 30 may be required, as the invention is not limited to a particular number of pistons and counterpart chambers.

Again referring to Fig. 4 of the drawing, the pistons herein disclosed are equal in 35 size, but unequally spaced. These pistons may be designated by the numeral 27. In this form of construction, the partition separating the rearmost piston chamber from the one next in advance is shorter than that 40 separating the last named chamber from the foremost chamber. From this explanation it will be understood that the pistons and their corresponding chambers may be unequal in size and volume. Where this is 45 the case, it is preferred that they should progressively diminish from the rear toward the front, as it has been found advantageous to exert the greatest force upon the rearmost part of the block or bulk of coal 50 to be broken down in a single operation. It will also be understood that the piston chambers may be equally or unequally spaced, as may be desired. Where they are 55 unequally spaced, the spacing should progressively increase from the rear toward the front for reasons which have been heretofore made clear.

From the foregoing description, the manner of employing cartridges of this 60 character for breaking down coal or other material in mines will be readily understood. By reference to Fig. 5, it should be explained that preparatory to introducing the cartridge, a cavity 28 is formed under- 65 neath a block of coal 29, the said cavity be-

ing preferably widest at its outer extremity as shown at 30, and diminishing toward the rear. Above this block of coal, a hole 31 is bored, into which the cartridge 5 is introduced. The water is then delivered to 70 the cartridge through the conduit 20 and the pistons of the cartridge ejected, whereby the block 29 of coal is broken down.

Having thus described my invention, what I claim is,—

1. A hydraulic cartridge comprising a body member having chambers elongated in the direction of the length of the cartridge, and pistons in said chambers and of counterpart shape, the said pistons and chambers being progressively larger from the 80 front to the rear of the cartridge.

2. A hydraulic cartridge comprising a body member having ellipsoidal shaped chambers, the longer axes of the chambers 85 being lengthwise of the cartridge, and pistons of counterpart shape located in said chambers, the chambers and pistons being variably spaced from the front toward the rear of the cartridge.

3. A hydraulic cartridge comprising a body member having a number of ellipsoidal shaped chambers, the longer axes of the chambers being parallel with the longitudinal axis of the cartridge, and pistons of 95 counterpart shape located in the said chambers, the chambers and pistons being variably spaced from the front toward the rear of the cartridge, the said spacing diminishing in degree progressively from the front 100 toward the rear.

4. A hydraulic cartridge comprising a body member having chambers of ellipsoidal shape, the longer axes of the chambers extending lengthwise of the cartridge, a number of pistons of counterpart shape located in said chambers, and the chambers diminishing in size progressively from the front to the rear, and variably spaced from the 105 front to the rear of the cartridge.

5. A hydraulic cartridge comprising a body having chambers elongated in the direction of the length of the cartridge, pistons of counterpart shape located in the said chambers and diminishing in size progressively from front to rear, the chambers being variably spaced and the spacing diminishing in degree progressively from the front 115 toward the rear of the cartridge.

6. A hydraulic cartridge comprising a 120 body member having chambers, pistons of counterpart shape located in said chambers, the chambers and pistons being variably spaced from the front toward the rear of the cartridge.

7. A hydraulic cartridge comprising a body member having a number of chambers, pistons of counterpart shape located in said chambers, the chambers and pistons being variably spaced longitudinally of the car- 13

tridge, the said spacing diminishing in degrees progressively from the front toward the rear.

8. A hydraulic cartridge comprising a body member having chambers, pistons in said chambers of counterpart shape, the said pistons and chambers being progressively larger from one extremity of the cartridge toward the other.

10. 9. A hydraulic cartridge comprising a body member having a number of chambers, pistons in said chambers, the said pistons being of counterpart shape, the pistons and chambers being progressively larger from the front toward the rear of the cartridge.

10. A hydraulic cartridge comprising a body member having a number of chambers, pistons in said chambers of counterpart shape, the pistons and chambers varying in size progressively from one extremity toward the other, the chambers and pistons being also variably spaced longitudinally of the cartridge. 20

In testimony whereof I affix my signature in presence of two witnesses.
